FIG. 3.

INVENTOR:

Nels Ekberg

BY A.M. Larsen

ATTORNEY.

UNITED STATES PATENT OFFICE.

NELS EKBERG, OF ST. PAUL, MINNESOTA.

DEVICE FOR LIFTING AND TOWING AUTOMOBILES.

Application filed March 31, 1924. Serial No. 703,034.

To all whom it may concern:

Be it known that I, NELS EKBERG, a citizen of the United States, residing at St. Paul, in the county of Ramsey and State 5 of Minnesota, have invented certain new and useful Improvements in Devices for Lifting and Towing Automobiles, of which the following is a specification.

My invention relates to wrecking cars 10 for automobiles and the object is to provide an easily operated and efficient device of said kind.

In the accompanying drawings;

Fig. 1 is a top plan view of my device as 15 used on the rear portion of a wrecking car and showing how its working parts are engaged with the front axle of an automobile.

Fig. 2 is a side elevation of Fig. 1 with the derrick of the wrecking car and other 20 parts added.

Fig. 3 is a section on the line 3—3 in Fig. 2.

Fig. 4 is a portion of one of the axle engaging devices of the derrick showing how 25 the same may be applied also to a round axle, or the tubular rear axle of an automobile.

Fig. 5 is a modification of the parts 28—29 in Fig. 1.

Referring to the drawings by reference numerals, 7 designates the supporting 30 wheels and 8 the axle of the rear end portion 9 of the body of a wrecking car.

Upon said body or platform 9 is erected 35 a swinging derrick comprising a mast 10 held upright by braces 11 and having a boom 12 adjustably connected to the mast by a block-and-fall 13 having its running rope 14 arranged for hoisting and for securing it as may be desired.

Suspended from the upper end of the boom 12 is another block-and-fall 15 having its running arm 16 adjustably secured to the mast by a cleat or like device 17 secured thereon.

Supported by the block 15 is a normally transversely arranged yoke 18, preferably of triangular form and suspended by one of its corners and a hook 18^a so as to present a horizontal, straight bottom edge near which are several apertures 19 in any of which may be engaged two hooks 20 of rods or elements 21 whose lower ends are pivotally secured to the upper ends of two cam levers 22, which are pivoted at 23 in

clevises 24 each of which has in its lower terminals a bolt 25 or other means adapted to engage in either one of several notches 26 in the under side or edge of either one of two lifting arms 27.

Said arms 27 are offset as at 27^a in Fig. 4, to clear certain springs (not shown) of the automobile, and they have each one end pivoted at 28 to swing horizontally in a short arm section 29 which may be curved some as at 30 in Fig. 5. These sections 29 are pivoted to swing in vertical planes on the ends 31^a of a short bar 31, which is swingable on a vertical pivot 32 in a forked draw-bar 33 which in the present case has a 70 round shank 34 journaled and retained by a pin 35 or other means in a bracket 36 fixed to the body 9.

Upon each rear end of the arms 27 is pivotally mounted at 37 a U-shaped fork 75 38 the top of which constitutes a clip and is closed by a lid or arm 39 hinged at 40 and held closed by a spring catch 41 when so desired.

In Figs. 1 and 2 is shown how an automobile axle 42 or other part of I-beam or similar shape may be engaged by the two clips 38, and the adjacent end of the car raised off of the ground as shown at 43 in Fig. 2 where the front wheels 44 of the automobile 45 are raised from the ground.

In Fig. 4 is shown how the rear axle housing or tube 46 or other cylindrical part of an automobile may be held in one or more 85 of the clips, 38.

In the operation or use of the device it is usually desirable to have the lifting tackle 15 as nearly as possible vertically over the front axle 42 of the damaged automobile 95 but in many cases the structure of the car does not permit of this and in such cases the terminal points 25 can not be in the notches 26 further to the left in Fig. 2 but must be moved toward the right, and in whichever notches the terminal 25 is placed it is held there against disengagement by jumping or sliding of the parts by the short end 22^a of the tilting cams 22 which have their longer arm attached each to the element 21 and is folded to horizontal position while the terminal 25 is being moved to the proper notch 26.

With the damaged car thus partly suspended the wrecking car is driven to the repair shop without being twisted or dam- 110

aged in any manner. The car is also saved from undue side strain by the arms 27, as they can be swung freely on the pivots 27-28, and from vertical strain by the joints 31^a, and from twisting strain by the journaled stem 34 in Fig. 2. When the car has reached its destination for repairs or other purposes it is lowered by and released from the derrick.

10 Where the structure or make of the damaged car permits or requires it, the space between the hooks 20 may be increased by moving them into the various holes 19, and if there is no chance to use both of the clevises 24 only one of them may be used and its hook 20 is then moved as near as possible to the middle of the row of holes 19.

What I claim is:

1. In a wrecking car for automobiles and 20 mounted on a motor truck, a derrick having a boom and a vertically adjustable yoke suspended therefrom and extending in transverse direction of the boom two spaced lifting devices suspended from the lower edge 25 of the yoke and having each pivoted to its lower end the longer arm of a cam lever, a clevis pivoted to the cam lever, two horizontally disposed arms extending each through one of said clevises and having 30 their forward ends spaced and pivoted to swing in a horizontal plane from the rear end of the wrecking truck, and U-shaped clips mounted to swivel in a horizontal plane upon the rear end of each of said arms 35 and adapted to receive and support some

horizontally disposed part of the damaged car.

2. The structure specified in claim 1, in which said arms have their lower sides provided each with several notches adapted to 40 engage the lower terminal of the clevis.

3. The structure specified in claim 1 in which said arms have their lower sides provided with several notches for the lower terminals of the clevises supporting them and 45 said cam levers arranged to hold each bar in engagement with said terminal when the cam lever is in raised position.

4. The structure specified in claim 1, in which the U-shaped clips on the rear ends 50 of the arms have each a hinged piece closing its top and a spring catch holding the hinged piece closed against accidental opening.

5. The structure specified in claim 1, in 55 which the forward ends of the arms are pivoted to an element swingable on a vertical pivot and provided with two horizontal pivots one for each of said arms.

6. The structure specified in claim 1, in 60 which the forward ends of the arms are pivoted to an element swingable on a vertical pivot and provided with two horizontal pivots one for each of said arms, and 65 said arms being each composed of a short piece pivoted to the swingable element and a longer piece pivoted to the short piece to swing in a horizontal plane.

In testimony whereof I affix my signature.
NELS EKBERG.
